PIEZO ELECTRIC CRYSTAL APPARATUS

Filed Aug. 16, 1929

UNITED STATES PATENT OFFICE

ERNEST R. HENTSCHEL, OF WASHINGTON, DISTRICT OF COLUMBIA; JOHN OLSON, ADMINISTRATOR OF SAID ERNEST R. HENTSCHEL, DECEASED, ASSIGNOR TO WIRED RADIO, INC., OF NEW YORK, N. Y., A CORPORATION OF DELAWARE

PIEZO-ELECTRIC CRYSTAL APPARATUS

Application filed August 16, 1929. Serial No. 386,440.

My invention relates broadly to piezo electric crystal apparatus and more particularly to a construction of dust proof holder for a piezo electric crystal element.

5 One of the objects of my invention is to provide a construction of piezo electric crystal apparatus wherein means are provided for mounting various sizes of piezo electric crystal elements at the same time that the casing 10 in which the selected piezo electric crystal element is mounted, is maintained in substantially closed condition and the crystal therein substantially protected.

Another object of my invention is to provide a housing for selected sizes of piezo electric crystal elements in which the selected piezo electric crystal element is free to vibrate with substantially no restriction and is maintained substantially closed for the protection 20 of the crystal element therein.

Other and further objects of my invention reside in the construction of piezo electric crystal mounting set forth in the following specification and shown in the accompanying drawing in which:

Figure 1 is a plan view taken on line 1—1 of Fig. 2 illustrating the piezo electric crystal element assembled within the piezo electric crystal holder according to the principles 30 of my invention;

Fig. 2 is a cross sectional view through the piezo electric crystal holder taken on line 2—2 of Fig. 1;

Fig. 3 is a plan view of a modified construction of mounting for piezo electric crystal elements of various sizes within a holder according to the principles of my invention;

Fig. 4 is a cross-sectional view taken through the modified construction of mounting on line 4—4 of Fig. 3; and

Fig. 5 is a cross-sectional view taken through the piezo electric crystal holder of Fig. 3 on line 5—5 thereof.

Heretofore in the art, housings for piezo electric crystals have been constructed which are adapted to receive piezo electric crystals of different sizes for the generation of oscillations at different frequencies but these housings have had a number of disadvantages inasmuch as they have not protected the piezo

electric crystal element against the entry of moisture and dust. This has been true by reason of the arrangement of permanent apertures through the bottom of the casing for the passage of textile cords therethrough, 55 which cords have been employed for the centering of the piezo electric crystal element within the housing. In prior crystal holders a portion of the retaining means for the piezo electric crystal has been necessarily external to the piezo electric crystal and moisture and dust seep through the apertures through which the external retaining means pass to the interior of the piezo electric crystal housing, thereby acting to the detriment of the 60 efficient operation of the piezo electric crystal element.

In my invention, I provide a completely closed housing within which the piezo electric crystal element is mounted and upon the 70 interior of the base of this housing I mount a supporting plate which is properly drilled and apertured for the passage of textile cords which are so disposed around the piezo electric crystal element that the piezo electric 75 crystal element may be centered within the housing and maintained free to vibrate without restriction at the same time that moisture and dust are excluded from the housing by reason of the fact that the centering means for the crystal are located wholly within the 80 housing and do not extend exterior thereof.

Referring to the drawing in detail, reference character 1 designates a metallic base member which protrudes upwardly at its center as indicated at 1a and extends interiorly in an upward direction within the housing formed by the cylindrical wall 22 of insulated material. The plate 1 carries piezo electric crystal mounting plate 2 which is secured in position upon the crowned or upwardly extending portion 1a of the plate 1 by means of screws 3. The portion 1a of plate 1 is diametrically grooved as indicated at 4, cooperating with a corresponding diametrical 95 groove in the supporting plate member 2. That is to say, a substantially semi-circular groove is cut in the portion 1a as shown at 5, and a corresponding groove is cut in the supporting plate 2 as indicated at 6. At right 100

angles to the grooves 5 and 6, I provide a pair of grooves 7 and 8, the groove 7 being diametrically cut in the upwardly extending portion 1a of plate 1 and the groove 1a being cut in the under surface of the supporting plate 2. The peripheral edges of the supporting plate 2 are slotted as shown at 9, 10, 11 and 12 to receive textile cords 14 and 15, enabling the cords to be stretched over the peripheral edges of piezo electric crystal elements of different sizes. The piezo electric crystal element shown at 16 has its upper surface covered and connected by means of contact plate 17, and the piezo electric crystal element with its aligned contact plate 17 is maintained centrally within the housing 22 by the textile cords 14 and 15 extending over the edges of the piezo electric crystal element 16 and beneath the supporting plate 2 for centering the piezo electric crystal within the housing 22.

It will be clear that the textile cords 14 and 15 may embrace piezo electric crystals of different sizes, the cords stretching around the peripheral edges and being drawn taut by means of hook 25 on upper member 24, which is anchored at its extremity in the notch 23 cut in the upper portion of one side of cylindrical wall 22. The textile cords are tied at any suitable point along the length thereof to form loops which may be resiliently supported by the hook member 25 around the sides of any selected piezo electric crystal element. The top of the contact plate 17 is connected at 18 to a flexible conductor 19 which connects to lug 20 on the protruding connection member 21 at one side of the casing. The plate 1 connects to pedestal member 34 by means of the screw 29 and the pedestal is secured at the opposite end by means of screw 28 which passes through the insulated top 26 of the housing. The pedestal 34 carries an extension member 30 which projects from the side of the casing 22 opposite to the projection 21 and by means of these oppositely disposed projections connection of the piezo electric crystal element within the mounting may be established.

The plate 1 is secured to the insulating housing 22 at other points about its periphery as indicated at 29a. The insulated top 26 of the housing is secured to the housing by means of screws 28a. Where the size of the piezo electric crystal elements which are to be used in the piezo electric crystal holder may be predetermined, as for example by selected frequency settings, at which the piezo electric crystal apparatus is to operate several pairs of apertures may be drilled or cut through the supporting plate 2 in predetermined positions. I have shown this modified construction in Figs. 3, 4 and 5, wherein the supporting plate 33 is notched at diametrically opposite positions indicated at 32 and is apertured by means of pairs of apertures indicated at 31 for the passage of textile cords

therethrough. The cords may then be passed through the grooves formed by the semi-circular cooperating grooves 5 and 6 in one direction and the cooperating grooves 7 and 8 in the opposite direction and passed through selected apertures 31 or around notch 32, depending upon the size of the piezo electric crystal element employed within the piezo electric crystal holder. Any desired number of apertures 31 may be provided in the plate 33 to accommodate the housing for the reception of piezo electric crystals of different sizes.

It will be seen that none of the apertures or grooves penetrate the lower base 1 so that the housing in which the piezo electric crystal is located is entirely closed against the dust or moisture and the piezo electric crystal element is thoroughly protected at the same time that the piezo electric element is free to vibrate without restriction. I may provide suitable gaskets between the ends of the cylindrical wall 22 and the metallic base member 1 and upper plate 26 in order to hermetically seal the piezo electric crystal holder.

In some instances it may be necessary to extend screws 28a from the top insulated closer plate 26 through the cylindrical wall 22 to the base plate 1 where the screws are soldered or otherwise secured for the hermetic closing of the housing.

The piezo electric crystal holder of my invention has been found to be highly practical in its construction and successful in its operation and while I have described particular embodiments of my invention, I desire that it be understood that modifications may be made and that I intend no limitations upon my invention other than are imposed by the scope of the appended claim.

What I claim as new and desire to secure by Letters Patent of the United States is as follows:

Piezo electric crystal apparatus comprising a base member, a hermetically sealed insulated housing carried by said base member, a metallic supporting plate member secured to the interior of said base member within said housing, a piezo electric crystal element having one face thereof in contact with said supporting plate member, a metallic contact plate in contact with another face of said crystal, said supporting plate member having diametral grooves cut in the face thereof in contact with said base member and extending substantially normal to each other, said base member having correspondingly aligned grooves cut therein, the face of said supporting plate member in contact with said crystal being multiply apertured near each end of each of said diametral grooves symmetrically with reference to a central point of said supporting plate member, supporting means attached to said housing, and flexible cords supported by said supporting means and passing through said diametral grooves in said sup-

porting plate and through apertures in the face thereof in contact with said crystal symmetrically disposed with reference to a central point of said plate member and disposed one near each end of each of said diametral grooves, whereby crystals of different sizes may be resiliently supported in said housing without contact with the medium outside said housing.

ERNEST R. HENTSCHEL.
